UNITED STATES PATENT OFFICE.

ALBERT M. WHEELER, OF CATLETSBURG, KENTUCKY.

COIN-CONTROLLED TOWEL DISPENSER.

Application filed April 25, 1923. Serial No. 634,573.

To all whom it may concern:

Be it known that I, ALBERT M. WHEELER, a citizen of the United States, residing at Catlettsburg, in the county of Boyd and State of Kentucky, have invented certain new and useful Improvements in Coin-Controlled Towel Dispensers, of which the following is a specification.

The invention relates to improvements in a roller towel cabinet having coin controlled mechanism whereby a clean length of towel may be drawn from the cabinet after the insertion of a coin of a given denomination therein.

15 It is an object of the invention to provide a roller towel cabinet having a carrying roll for the clean towel and a winding roll for the used portion of the towel, with interposed coin controlled actuating mechanism 20 for permitting a section of clean towel of a given length to be withdrawn from the towel carrying roll upon the deposition of a coin of a given denomination in the apparatus.

25 With the foregoing conception in mind the invention preferably comprises a towel cabinet wherein the clean sections are successively advanced after the deposit of each coin in the apparatus and the used or soiled sections are continuously wound on the winding roll of the mechanism.

In carrying out this invention I provide improved mechanism for releasing the towel when a coin has been inserted in the mechanism and for simultaneously operating the winding roll to take up a previously used section of the towel. Said mechanism comprises simple and inexpensive means actuated by a lever engaging the coin, and serving to operate means adapted to directly cooperate with the feeding section of a towel whereby the towel is directly engaged after a given length has been withdrawn until a second coin is inserted in the machine.

35 My invention further comprises improved and simple means for accomplishing the above ends as will be more fully hereinafter set forth in the specification and drawings.

In the drawings Figure 1 represents a 40 cross sectional view taken transversely through the apparatus.

Figure 2 discloses a longitudinal section; Figure 3 illustrates a detail view; and Figure 4 is a front view.

45 Referring now more particularly to the drawings wherein like reference characters

indicate corresponding parts, the numeral 1 designates a cabinet which is adapted to be suspended on a wall or the like and which has a towel exit 2 on its front face and a 50 similar slot 3 through which a used portion of the towel enters the cabinet. The towel is adapted to pass from the cabinet through the slot 2 and drop down along the front of the slot a sufficient distance to provide 55 a towel section suitable for the desired purposes, the used sections of the towel constantly feeding back to the cabinet. 4 is a coin receiver into which a coin of a suitable denomination is inserted when an unused 60 section of the towel is to be fed, a lever 5 being operated after the insertion of said coin.

The mechanism for feeding the unused 65 sections of the towel and for winding the used sections thereof, comprises a feeding roller 6 journaled in the casing 1 near its upper end and cooperating with a winding roller 7 by means of the meshing gears 8. The roller 7 is journaled in the housing and 70 is parallel with the roller 6. The towel is wound upon the roller 6 and a roll with the towel then placed in the cabinet or housing 1. The towel is then passed around a drum 9, over the feeding roll 10 through the slot 2, thence back through the slot 3 between the roll 10 and the roller 11 and into the receptacle or casing 1, from where is it attached to the winding roller 7 so that when the roller 6 is operated to unwind an unused section of the towel the roller 7 is likewise rotated in an opposite direction to wind the used sections of said towel. During the beginning of an operation when a new roll of towel has been inserted in the 80 apparatus, some section of the used towel will accumulate in the casing 1 because of the fact that the roller 7 is of substantially less diameter than the roller 6 with its contained towel, but as the roller 6 unwinds to feed the towel, its diameter will decrease, while the diameter of the towel on the roller 7 will correspondingly increase, whereby at the time an entire strip of towel has been 85 used, it will be entirely wound on the roll 7. 100

Referring now to the feeding mechanism for the towel whereby sections of a given length are intermittently advanced, said mechanism comprises coin control means as clearly shown in Figure 1. Said means includes a coin slot 12 having therein an abutment 13 constituting a stop for the coin 110

when fed to said slot. When a coin has been fed it travels to the abutment 13 whereupon the pivoted lever 5 has moved downwardly against the tension of the spring 14 until 5 the plunger 15 engages the coin and forces the same downwardly out of contact with the abutment 13. This downward movement is transmitted to a reciprocating rod 16 pivoted at its end to a towel engaging 10 latch 17, which latch is mounted on the shaft 18. The shaft 18 extends across the casing 1 being journaled in a bearing 19 at one end, while a bearing 20 is provided at the opposite end thereof, said shaft being 15 formed with a collar 21 having interposed between said collar and the bearing a spring 22, serving to keep the shaft properly positioned for reasons which will hereinafter appear. The latch 17 is secured to the shaft 20 intermediate its ends so that the pointed locking end 23 thereof directly engages the towel feeding around the drum 9. When the lever 5 is shifted as described, this causes the latch 17 to be raised to its elevated position as shown in full lines in Figure 2 and 25 out of contact with the towel. The towel may then be pulled forwardly manually by the user, causing an unwinding of the roller 6 and a rotation of the drum 9 in the direction of the arrow. This movement of the towel continues until the latch 17 is shifted to engage the towel and arrest its movement by mechanism to be now described.

The drum 9 at one side thereof carries an 30 outstanding trip 25 which is adapted to rotate with said drum and which trip engages and cooperates successively with the elements 26 and 27 fixed to the shaft 18 and spaced from one another. The drum and 35 trip mechanism is so constructed that the drum will rotate twice before the latch is shifted to its dotted line position, to engage the towel and prevent movement thereof. If the coin has just been inserted in the slot 40 45 and the latch raised the towel is withdrawn by the operator rotating the drum until the trip 25 engages the first element 27 connected with the shaft 18, which shifts the latch to the full line position X, but at which position, of course, it does not so engage the 50 towel as to lock it against forward movement. The drum 9 continues to rotate and the trip 25 on its second revolution engages the element 27 which has been moved to 55 engaging position by reason of the engagement between the trip 25 and the element 27 and the continuous rotation of the drum causes this element 27 to be brought down to such a position as to bring the point 23 60 firmly into contact with the towel passing over the drum 9 as shown in dotted lines, and as this latch is beyond center, any pulling movement of the towel merely causes the towel to be more tightly locked to the drum 65 and prevents further movement thereof.

The user may then freely use the section withdrawn from the apparatus and the apparatus is locked until a second coin is inserted in the coin slot. During the operation herein referred to the roller 7 is, of course, 70 rotating and the unused towel from a previous operation is being wound on said roller so that when an entire roll of towel from the roll 6 has been used the used towel is at the same time wound upon the roller 7 so that the two rollers may be removed and a new roll of towel substituted in the cabinet along with a new winding roll 7.

It is thought that the operation of the apparatus can be clearly understood from the foregoing description of its parts, but the said operation may be briefly recited as follows:

A coin is inserted in the coin slot 4 and the pivoted lever 5 operated. This depresses the plunger 15 causing the same to engage the coin, shifting the rod 16 which is connected to the shaft 18. The shaft is therefore rocked, lifting the latch bar 23 to the full line position in Figure 1, whereby it is disengaged from the towel. This releases the towel and the section can be withdrawn rotating the drum 9. The towel is continuously withdrawn until this drum has made two revolutions. During one of these revolutions the trip 25 engages the element 26 imparting a movement to the shaft 18 sufficient to move the latch 23 one-half of its distance toward its operative position and on the second revolution of the drum 9 the trip 25 engages the element 27 and the movement of this element causes the latch to be brought down to the full dotted line position and into direct contact with the towel, locking the drum 9 against further movement. During this movement of the drum 9 the winding roller 7 is being wound so that a previously used section of the towel is wound on the said roller. The drum 9 will remain locked until a second coin is inserted in the coin slot and the lever 6 operated to release the latch 17 from the drum.

Having thus described my invention, what I claim is:

1. In a towel vending machine, the combination with a casing, of a delivery roller therein, a take-up roller disposed within said casing and geared with said delivery roller, a drum around which the towel passes when being delivered from said delivery roller and coin control means for controlling the withdrawal of towel sections from said casing including a shaft adjacent said drum, a latch connected with said shaft, means operable through the agency of a coin for shifting said shaft to raise the lever to an inoperative position to permit withdrawal of a towel section and means for moving said latch to an operative position for en-

gagement with the towel when a predetermined section has been withdrawn including a trip carried by the drum adapted to cooperate with means carried by said shaft to lower the latch into binding engagement with the towel and the drum.

2. In a towel vending machine, the combination with a casing, a delivery roll upon which the towel is placed, a take-up roll 10 geared to said delivery roll and adapted to be connected with one end of the towel, a drum around which said towel passes, openings in the casing for the passage of the towel from the casing and back into the casing, coin control means for controlling the withdrawal of the towel from said casing including a shaft, a latch carried by said

shaft, means operative upon the insertion of a coin for shifting the shaft to raise the same to an inoperative position to permit a movement of the towel around said drum, and means for controlling the length of the towel to be withdrawn from the casing comprising a trip connected with the drum, and successive elements connected 25 with said shaft adapted to be successively operated upon successive rotations of the drum to bring said latch into normal operative relation with the towel and the drum to lock said towel against further withdrawal.

In testimony whereof I affix my signature.

ALBERT M. WHEELER.
